UNITED STATES PATENT OFFICE.

RUDOLPH KRENZ, OF MIDDLETOWN, CONNECTICUT, ASSIGNOR TO THE RUSSELL MFG.
CO., OF MIDDLETOWN, CONNECTICUT, A CORPORATION.

SELF-CONTAINED INDIVIDUAL COP-WINDER.

1,260,000.

Specification of Letters Patent.

Patented Mar. 19, 1918.

Application filed May 29, 1917. Serial No. 171,652.

To all whom it may concern:

Be it known that I, RUDOLPH KRENZ, a citizen of the United States, residing at Middletown, in the county of Middlesex 5 and State of Connecticut, have invented a new and useful Improvement in Self-Contained Individual Cop-Winders; and I do hereby declare the following; when taken in connection with the accompanying drawings and the characters of reference marked thereon, to be a full, clear, and exact description of the same, and which said drawings constitute part of this application, and represent, in—

15 Figure 1 a view partly in side elevation and partly in section, of a self-contained individual cop-winder embodying my invention.

Fig. 2 a view of the driving or rear end thereof.

20 Fig. 3 a view thereof in vertical transverse section on the line 3—3 of Fig. 1, looking in the direction indicated.

Fig. 4 a view thereof in vertical transverse section on the line 4—4 of Fig. 1, looking in the direction indicated.

Fig. 5 a detached view in elevation of the thread - feed pulley with a portion of it broken away to show the eccentric crank-pin.

30 Fig. 6 a detached perspective view of the winding-cone.

My invention relates to an improved cop-winder, the object being to produce a self-contained individual cop-winder adapted in size and form to be applied directly to a loom so that the weaver may supply himself with the cops required for his work.

With these ends in view, my invention consists in a self-contained individual cop-winder having certain details of construction as will be hereinafter described and pointed out in the claims.

In carrying out my invention as herein shown, I employ a cop-winding spindle comprising a body-portion 2 and a tapering polygonal point 3. This spindle is journaled at its rear end in a bearing 4 at the upper end of an upright 5 at the rear end of the machine-frame 6. The forward end 45 of the spindle is journaled in a bushing 7 located within the cylindrical stem 8 of the winding-cone 9 which is formed as usual with a thread-slot 10, the said stem being secured by a set-screw 11 within a hub 12 located near the lower end of the main upright

13 of the machine-frame. The spindle is driven by a driving pulley 14 secured to it by a set screw 15 and formed at its forward end with a grooved extension 16 receiving a round belt 17 running over a grooved thread-guide pulley 18 turning on a stud 19 fixed in a head 20 at the upper end of the main upright 13 of the frame 6. The said pulley 18 is provided with a crank-pin 21 projecting from one side of the center of a 60 stud 22 adjustably mounted in the pulley and secured in any position of adjustment therein by a set screw 23. The crank-pin 21 carries a crank-head 24 secured in place upon it by a cotter-pin 25 and receiving the 65 bent upper end 26 of a crank-rod 27 the lower end 28 of which is bent at a right angle and passed transversely through the head of a rocking-stud 29 journaled in a boss 30 formed at the outer end of a thread-guide lever 31, rocking upon a stud 32 in the main-frame 6. The said lever 31 is formed with a segmental slot 33 receiving a binding-screw 34 which passes through the 70 said slot and into a thread-guide arm 35 the 75 lower end of which also rocks upon the stud 32. The upper end of the said arm 35 carries a thread-guide 36 secured in place by a screw 37, and extending upward and over the thread-slot 10 in the winding-cone 9. 80 By means of the segmental slot 33 and the screw 34, the arm 35 may be adjusted with respect to the rocking-lever 31, and hence 85 changed in the position of its throw.

The driving-belt 38 running over the pulley 14, is automatically shifted to a loose pulley 39, also mounted upon the spindle 2, by means of two belt-shifting arms 40 suitably spaced apart and rising from a wide collar 41 secured to a longitudinally 90 movable belt-shifter rod 42 bearing at its rear end in the upright 5 and at its inner end in the lower end of the main upright 13, the forward end of the rod having an upstanding operating manual or handle 43. 100 The said rod is prevented from rocking by means of an arm 44 secured to it by a set screw 45 and having its lower end perforated for the reception of a rocking tripping-rod 46 over which it rides back and 105 forth.

For the purpose of automatically stopping the machine upon the completion of the winding of a cop, I employ a beveled cut-off or tripping-lever 47 secured to the rocking 110

tripping-rod 46 upon which it is adjusted according to the length of the cops to be wound, the said rod 46 having bearing at its rear end in the upright 5 of the frame and 5 at its forward end in a bracket 48 secured to a fixed rectangular slide-bar 49, the rod-like rear end 50 of which passes through a bore 51 in the lower end of the main upright 13, and a bore 52 in the upright 5. The bar 49 10 is located below the spindle and the winding cone and in the vertical plane thereof. At its rear end the rod 46 is provided with a latch-finger 53 secured to it by a set screw 54 and adapted at its upper end to enter a 15 notch 55 in the inner face of the belt-shifter rod 42. A helical spring 56 connecting the said screws 45 and 54, exerts a constant effort to draw the rod 42 rearward so as to cause the belt-shifter to transfer the belt 38 20 from the driving pulley 14 to the loose pulley 39. A helical spring 57 secured at its upper end to an eye 58 in the upright 5 and at its lower end to an arm 59 applied to the projecting rear end of the rod 42, ex- 25 erts a constant effort to rock the said rod and cause the latch-lever 53 to enter the notch 55 in the belt-shifter rod 42. The slide-bar 49 aforesaid, carries a slide 60 having an upright 61 supporting a horizontal tubular 30 bearing 62 mounting a rotatable trunnion 63 centering and supporting the cop-but 64, the trunnion 63 having a circumferential groove 65 receiving a retaining-screw 66. A finger-piece 67 depending from the bearing 62, provides for manually moving the slide away from the winding-cone 9 and against the power of a weight, not shown, but carried by a cord 68 secured to the slide by an eye 69 and running over a pulley 70 40 on a stud 71 in the frame 6.

A thread-hook 72 located substantially above the thread-guide 36 is mounted in the upper end of the main upright 13 in which it is secured by a set screw 73.

45 In using my improved machine, the slide 60 is moved by its finger-piece 67, away from the winding-cone 9 against the power of the weight attached to the cord 66, so as to clear the winding-cone and permit a cop- 50 butt to be forced over the tapered end 3 of the winding-spindle, one end of the yarn to be wound into a cop having previously been attached to the cop-but. The manual 43 is now grasped and the rod 42 slid forward to the limit of its throw in that direction, whereby the belt 38 is shifted from the loose pulley 39 to the driving pulley 14, thus starting the spindle rotating and the thread-guide lever and arm rocking. As the belt-shifter 55 rod 42 reaches the limit of its forward movement the spring 57 forces the latch-lever 53 into the notch 55 of the rod, whereby the belt-shifter is locked in its driving position. Now as the cop-tube is built up in the usual 60 manner, the pressure of its inner or building

end against the interior walls of the winding-cone, gradually moves the slide 60 outward against the power of the weight depending from the cord 68. This continues until the said slide engages with the tripping or cut-off lever 47 and depresses the same sufficiently to rock the rod 46 against the tension of the spring 47 and so disengage the latch-lever 53 from the notch 55 in the belt-shifter rod 42. The spring 56 now asserts itself to pull the rod 42 rearward so as to shift the belt 38 from the driving pulley 13 to the loose pulley 39, whereby the machine is stopped. 70 75

The diameter of the cop-tube thus produced is determined by the throw of the thread-guide arm 35 which is regulated by shifting the position of the crank-pin 21 by turning the stud 22 in the thread-guide pulley 18. The position of the throw of the thread with respect to the winding-cone 9 is regulated by the segmental slot 33 and binding-screw 34 which permits the thread-guide arm 35 to be shifted in position with respect to the rocking thread-guide lever 31. 80 85 90

By my improved construction and arrangement of parts, I am enabled to produce a thread-guide so compact in form and requiring so little space for its operation, that it may be applied to an ordinary loom without interfering with the full and free use of the same, whereby a weaver is enabled to wind his own cops. In my improved device, I dispense with the use of the train of gears generally employed for driving the thread-guide. It will also be noted that the train of parts operating the thread-guide mechanism is located substantially above the cop-winding spindle and winding-cone rather than to the side thereof as heretofore. 95 100 105 It will be further noted, that by employing a slide on a slide-bar, the space required for the operation of the machine is much reduced over that required for the operation of machines employing a longitudinally movable slide-bar carrying at one end a fixture provided with the trunnion used for centering and supporting the cop-but. 110

I claim:—

1. In a self-contained, portable individual cop-winding machine, the combination with a horizontal frame having upstanding bearings and an upright and adapted to be mounted in a horizontal position upon a loom-frame, of a cop-winding spindle located above the said frame and journaled in the said upstanding bearings, a winding-cone concentric with the said spindle, a movable thread-guide, a driving pulley concentric with the said spindle, and driving means 120 mounted upon the said upright for operating the said thread-guide. 125

2. In a portable self-contained individual cop-winding machine, the combination with a frame adapted in form and size to be 130

- mounted upon a loom, of a cop-winding spindle, a winding-cone, a driving pulley mounted upon the said spindle, a rocking thread-guide, an upright of the frame extending substantially above the said spindle and cone, a thread-guide pulley mounted in the upper end of the said upright, a belt between the said pulleys, and adjustable connection including a crank-rod between the 5 thread-guide pulley and the thread-guide for the operation of the latter, all of the said parts being arranged and assembled above the base of the frame to permit the same to be applied to a loom.
- 10 3. In a self-contained, portable individual cop-winding machine, the combination with a horizontal frame having upstanding bearings and adapted to be mounted in horizontal position upon a loom-frame, of a cop-winding spindle located above the said frame and journaled in said upstanding bearings, a winding-cone concentric with the said spindle, a slide-bar parallel with the said spindle and located in a plane between the said 15 frame and spindle, a slide mounted upon the said bar by which it is maintained in an upright position, a cop-butt trunnion carried by the said slide which is moved on the said slide-bar away from the said winding-cone by the cop as the same is built up in the 20
- 25
- 30
- said cone, a belt-shifter located above the plane of the frame and controlling the driving of the said spindle, and an automatic stop operated by the said slide in its outward excursion and connected with the said belt-shifter for the operation thereof on the completion of the cop. 35
4. In a portable self-contained individual cop-winder, the combination with a frame adapted in form and size to be mounted upon a loom, of a cop-winding spindle, a winding cone, a thread-guide, means for operating the same, a belt-shifter controlling the rotation of the winding spindle, a slide operated by the cop as it is gradually built up in the said cone, and an automatic stop operated by the said slide and comprising a cut-off lever, a rock-shaft, and a latch which latter co-acts with the belt-shifter, all of the said parts being arranged and assembled above the base of the frame to permit the same to be applied to a loom. 40 45 50

In testimony whereof, I have signed this specification in the presence of two subscribing witnesses.

RUDOLPH KRENZ.
